CLAIM

The ornamental design for a cap seal for bottle cap, as shown and described.

DESCRIPTION

FIG. 1 is a top front perspective view of a cap seal for a bottle cap showing our new design;

FIG. 2 is a front view of the cap seal illustrated in FIG. 1;

FIG. 3 is rear view of the cap seal illustrated in FIG. 1;

FIG. 4 is a top view of the cap seal illustrated in FIG. 1;

FIG. 5 is a bottom view of the cap seal illustrated in FIG. 1;

FIG. 6 is a left side view of the cap seal illustrated in FIG. 1; and,

FIG. 7 is a right side view of the cap seal illustrated in FIG. 1.

The broken lines show portions of the design that form no part of the claimed design.
